UNITED STATES PATENT OFFICE

FRED BIFFAR, OF CHICAGO, ILLINOIS

DESIGN FOR A CAP FOR A PEN OR SIMILAR ARTICLE

Application filed May 27, 1929. Serial No. 31,414. Term of patent 7 years.

To all whom it may concern:

Be it known that I, FRED BIFFAR, a citizen of the United States, residing at Chicago, in the county of Cook and State of Illinois, have invented a new, original, and ornamental Design for a Cap for a Pen or Similar Article, of which the following is a specification, reference being had to the accompanying drawing, forming a part thereof.

Fig. 2 is a side elevation thereof.

I claim:

The ornamental design for a cap for a pen or similar article substantially as shown.

FRED BIFFAR.
